METHOD OF MAKING TUBES

Harry C. Hackett, Wilmington, Del., assignor to
National Vulcanized Fibre Co., Wilmington,
Del., a corporation of Delaware

Application September 20, 1937, Serial No. 164,800

3 Claims. (Cl. 154—2)

The present invention relates to the making of tubes and more particularly to the making of vulcanized fibre tubes having relatively thick walls.

In the manufacture of tubes made of vulcanized fibre and other chemically treated material in sheet form the general practice has been to wind the material upon a mandrel until it has reached the required diameter, with due allowance for shrinkage and while this is satisfactory for tubes having relatively thin walls it is most unsatisfactory where a thick or heavy wall tube is desired. Heretofore tubes of thick walled construction made by this ordinary method blister and crack so that one layer of material is circumferentially out of contact at various points with the next adjacent layer of material, or there are radial cracks through several layers. While there seems to be no general rule as to the number of layers which can be successfully wound without blistering and cracking because of the various diameters of finished tubes, it is well known that up to a certain relatively thin wall thickness no such defects appear. On the other hand as soon as wall thicknesses beyond this safe maximum thickness are called for, present day methods fail to prevent the layers of material cracking during the drying and finishing steps.

Some of the objects of the present invention are to provide a method of tube making wherein perfect tubes of any desired thickness can be successfully made; to provide a method wherein cracking, blistering and like defects in tubes of laminated construction are eliminated; to provide a method of tube making wherein thick walled tubes can be made as perfectly as tubes having thin walls; and to provide other improvements as will hereinafter appear.

In the accompanying drawing Fig. 1 represents a perspective of a tube as partially formed in accordance with the present invention; Fig. 2 represents a perspective of the tube of Fig. 1 mounted upon a mandrel; Fig. 3 represents diagrammatically the step following the stage represented by Fig. 2; and Fig. 4 represents a portion, in perspective, of a finished thick walled tube embodying the method of the invention.

Referring to the drawing those steps believed helpful in the understanding of the present invention are illustrated and in the following description the making of a vulcanized fibre tube is taken as an example of the application of the invention. The first stage in the method consists in making a complete finished tube 10 having a relatively thin wall. Such a tube 10 is

made by winding upon a mandrel the required number of convolutions or layers of treated open stock to make a tube of given thickness after shrinkage losses are allowed. Ordinarily the stock is drawn from a roll passed through a treating bath containing a gelatinizing agent, such as a suitable acid and wound on the mandrel to predetermined thickness when it is automatically severed and the wound mandrel removed. The tube is now pured, dried and rolled so that the result is a completely finished tube 10 with a relatively thin wall having no breaks or cracks therein. A mandrel 11 is now inserted in the finished tube 10 and the latter then placed in the winding or forming machine. One form of such machine is indicated in Fig. 3 wherein driven rollers 12 and 13 support the tube 10 in surface contact therewith. The paper stock length 14 is drawn from a stock roll 15 passing through a treating bath 16 of the character noted to wind about the tube 10 and form the encompassing tube portion 17. The desired cohesion between the surface of the tube 10 and the stock 14, as well as the succeeding layers of stock is brought about through pressure applied through the roll 18, and the action of the treating acid which causes the surface of the finished tube to knit into the first superposed layer to form a perfect union. This winding operation continues until the thickness of material superposed about the tube 10 will, after shrinkage, give a tube of the predetermined diameter and wall thickness. Following this winding operation the tube is removed to soak in a purifying bath until all excess treating liquid is leached out after which the tube is placed in a drier and thereafter submitted to a rolling under calender rolls whereby to finish the same at the final dimension desired. The shrinkage which occurs during the drying action is restricted to the secondary winding of material since the first winding has completed its shrinking when first subjected to the drying operation. It has been discovered that a tube made in accordance with the present method has its outer series of plies tightly laminated to the surface of the inner series of plies, the two surfaces being perfectly cohered throughout the whole area. Thus while the completed tube consists of two separately formed portions 10 and 17, one encompassed by the other, the joint or seam between the two sets of plies is invisible and the effect, not only to the eye but as a physical fact, is that of a unitary tube having a thick wall devoid of blisters, cracks, irregularities or other imperfections ordinarily

found in tubes of like thickness made by prior methods.

While the foregoing describes the making of a tube through two successive winding operations, 5 one following a completed tube, the invention is not limited in this respect in that a series of winding can be made if found expedient. That is to say each series may become a finished tube to be used as a mandrel for another series, and 10 in this way a unitary wall of maximum thickness can be built up free from cracks and other defects now normally present in tubes of corresponding thickness made by methods heretofore practised.

15 Having thus described my invention, I claim:—

1. The method of making a vulcanized-fibre tube having a relatively thick wall from strip material which consists in first forming a relatively thin walled tube by chemically treating 20 the strip with a gelatinizing agent, winding, puring, drying and rolling the wound strip material to produce a finished tube of a limited dimension, and thereafter using said tube as a mandrel and winding on it additional layers of 25 similarly treated strip material to build up the tube to a desired dimension, and puring, drying, and rolling the tube to finish the same at its final dimension whereby the thick walled tube formed thereby will not blister or crack.

2. The method of making a vulcanized-fibre tube having a relatively thick wall from strip material which consists in first forming a relatively thin walled tube by chemically treating the strip with a gelatinizing agent, winding, puring, 5 drying and rolling the wound strip material to produce a finished tube of a limited dimension, and thereafter using said tube as a mandrel and winding on it additional layers of similarly treated strip material to build up the tube to a desired dimension, applying pressure during the winding operation, and puring, drying, and rolling the tube to finish the same at its final dimension whereby the thick walled tube formed thereby will not blister or crack. 15

3. The method of making a vulcanized-fibre tube of strip material having a relatively thick wall free from blisters and cracks which consists in forming a relatively thin walled finished tube of vulcanized-fibre strip material of a dimension 20 where the possibility of blistering or cracking is minimized, and thereafter using said tube as a mandrel and winding on it additional layers of chemically treated strip material to build up a relatively thick walled tube of the desired dimension, and puring, drying and rolling the tube to finish the same at its final dimension. 25

HARRY C. HACKETT.
